(57) **CLAIM**

The ornamental design for a magnifying glass, as shown and described.

DESCRIPTION

FIG. 1 is a perspective view of the magnifying glass showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof when it is being used; and,

FIG. 10 is a perspective view thereof when it is being used from another angle.

The broken lines shown in the drawings represent portions of the magnifying glass that form no part of the claimed design.
